PENNSYLVANIA, A CORPORATION OF PENNSYLVANIA.

ELECTROMAGNETICALLY-CONTROLLED BOARD DROP-HAMMER.

1,311,942.

Specification of Letters Patent.

Patented Aug. 5, 1919.

Application filed October 30, 1917. Serial No. 199,259.

To all whom it may concern:

Be it known that we, ARTHUR ALDRIDGE and HOWARD TERHUNE, citizens of the United States, residing at Chambersburg, in the county of Franklin and State of Pennsylvania, have invented a certain new and useful Electromagnetically - Controlled Board Drop-Hammer, of which the following is a specification.

10 The purpose of our invention is to provide electric control for a board drop hammer, relieving from the jar of tappet actuation of the parts required to secure roll movement and maintain the rolls in engagement 15 with the board.

A further purpose is to provide gravity release for the rolls instead of gravity setting thereof, reducing the weight of parts required and throwing the rolls to released position in case of failure of the roll-setting mechanism.

20 A further purpose is to provide interchangeably for brush actuated contact or positive switch throw to make and break the contacts to energize and deenergize the electromagnetic clutch operating mechanism.

25 A further purpose is to use a solenoidal electromagnetic resilient pull for the initial movement and major part of the clutch setting throw of the board engaging rolls and to supplement the solenoidal pull of an electromagnet at the end of the stroke in order to make the engagement of the rolls with the board more positive. In this connection we 35 cause compression of a releasing spring during the setting movement of the solenoid and use this spring to assist in quick release of the rolls from the board when the current is withdrawn.

40 A further purpose is to combine solenoidal and electromagnetic pull and retention of the rolls in their setting engagement with the board and to combine spring and gravity operation for the release when the electric 45 current is cut off.

Further purposes will appear in the specification and in the claims thereof.

Our invention contemplates the methods involved as well as the apparatus in connection with which the methods are explained.

We have preferred to illustrate our in-

vention by but one form, selecting for the purpose a form which in use has proved to be practical, efficient and inexpensive, and which at the same time well illustrates the principles of our invention.

Figure 1 is a front elevation omitting some of the well known parts of the preferred form of our invention.

Fig. 2 is a side elevation, partly broken away, of the structure seen in Fig. 1, but with the omitted parts shown.

Fig. 3 is an enlarged section of a portion of the structure, seen in Fig. 1.

Figs. 4 and 6 are sections taken upon the lines 4-4 and 6-6 in Fig. 1.

Fig. 5 is a perspective view of one of the parts seen in Fig. 3.

In the drawings similar numerals indicate like parts.

The side frame members 6-6, base 7, lower die 8, treadle 9 and connections 10 are all old and the latter release an old form of board clamps through the medium of a rod 11. The rear one of the board clamps and the rear roll of the board rolls are capable of adjustment as in previous hammers by means of adjusting bars 12, 13 respectively held and shifted by the usual devices. At their upper ends these bars connect with adjusting levers 14 and 15 to turn eccentric shaft-carrying sleeves within bearings as before. The shifting of the front clamp of the board clamps by the treadle and the driving of the board rolls have not been changed.

In existing drop hammers with which we are familiar the shaft of one of the board rolls, preferably the front roll, is carried by an eccentric sleeve or mount which is oscillated within a fixed outer bearing by a heavy front rod or friction bar to move that roll toward and away from its mate so that both will grip the board 16 to lift or release it and the ram 17. In these hammers the weight of the front rod and connections are relied upon to keep the rolls in operative engagement with the board, and the ram or a part connected therewith must lift this heavy rod and the connections by a blow during the upward stroke to throw the roll into the release position. The constant jarring causes fatigue of the affected

parts, resulting in breakage and failure of operation. Our invention is intended to replace the weight control by electromagnetic control, to use electric connections, 5 with or without mechanical switch actuation, instead of the purely mechanical tapet actuation of the rod, preferably lifting the roll-sleeve arm for roll engagement instead of lowering it (or over counterbalancing the arm if it be lowered, so that there shall be gravity or spring return to released position) and to supply quick release when the current is interrupted.

The roll-carrying eccentric sleeves 18 for 15 the front roll are preferably oscillated within its bearing 19 a short distance only to throw the center of the roll shaft to opposite sides of a perpendicular line through the eccentric center.

20 Among the many forms in which the electric current could be utilized to throw eccentric arm 20 we have preferred to use the form in which the electro-magnetic device, exemplified in combined electromagnet 25 and solenoid 21, lies above the arm, in order that the weight of the parts may cause release of the rolls in case of failure of the electric current.

The electromagnetic device 21, best seen 30 in Fig. 3, is of the iron-clad type including an outer shell 22 intended to act as part of the magnetic circuit and made of iron for this purpose. It carries an inwardly directed magnet pole 23 and provides a 35 space outside the pole and inside the shell for a winding 24, hollow at 25 below the pole, intended to energize the magnet pole and at the same time form a solenoidal extension.

40 The solenoid and magnet pole both act upon the same armature 26 of magnetic material.

For convenience, and to permit the use of a poorer quality of material for the rod 27, 45 the latter is made separate from the armature. It is guided in bracket 28 and is connected at its lower end with an arm 29 pivoted at 30.

We have shown the magnet shell as circularly ribbed at 31 to improve its qualities as a distributor of heat, and have indicated a non-magnetic strip at 32 to reduce undesirable leakage of magnetic line.

The pin 33 connects between rod 27 and 55 the arm 29. As the rod is guided to move in a straight line and the arm swings about an arc we have arranged for a sliding connection between the parts, while permitting a well balanced thrust and firm engagement.

60 Each of the sides 34, 35 of the arm is slotted, as at 36, 37 to receive flattened ends of the pin 33 and to give a firm bearing to the flat sides of the pin in each direction of movement while permitting free sliding

movement lengthwise of the sides. The central part of the pin is left cylindrical to fit within the socket 38 upon the end of the rod. The pin is inserted through either of the cylindrical passages 39, 40 which communicate with the slots and make them, in effect, keyhole slots.

The sides of the arm 29 are stiffened by a connecting rib 41 and are extended to give support at 42 and 43 to a pin 44 by which arm 29 is connected to link 45. At its lower end the link is connected by a pin 46 with eccentric arm 47.

It will be seen that the armature and connected parts will be lifted from the position shown in Fig. 3, in which the rolls are released from the board, to the roll-engaging position by electromagnetic action which is almost wholly solenoidal at the start and largely by a magnet at the upper end of the stroke, making it possible to secure full contact between the face 48 of the magnet pole and the end 49, of the armature when in full clutching position, if actual contact be desired.

Even if contact be avoided because of the danger of sticking, this affords a pull of increasing strength as the upper position is approached, with a maximum hold when the armature is at its uppermost position and the rolls should most tightly engage the board 16.

It will also be seen that the weight of the armature and connected parts will combine to drop the arm 29 and to release the rolls from engagement with the board when the electric current is interrupted, whether by normal operation of the hammer or by accidental or unauthorized interruption of the circuit.

Because of the desirability of a quicker release than would be provided by gravity alone, we interpose a spiral spring 50 between any suitable shoulder or projection 51 upon the rod, and a relatively fixed member such as the lower part 52 of the bracket 28. This, of course, necessitates design of an electromagnetic circuit with sufficient strength to compress the spiral spring in addition to lifting the armature and connected parts.

Physical contact between the armature and the pole face, desirable on account of the greater intensity of the magnet hold secured thereby, would increase the desirability of using a quick-release.

It will be obvious not only that the form of electromagnetic pull and connections for operating each roll thrown may be varied greatly but also that the variety of means for making and breaking the electric current required is great, varying from the most simple form of co-operating switch members, one part being carried by the ram,

to complicated forms of switches, mechanically operated by means connected with the ram.

The invention is preferably illustrated by 5 a mechanically operated switch, for which cam operation and an oscillatory shaft have been selected in preference to other forms that will suggest themselves to any designer in the art, because by this construction 10 bodily movement need not be given the shaft by the ram, thus reducing the amount of work to be performed in the movement of the switch operating mechanism.

Describing now the preferred form of 15 contact making device, the electric connections are protected by the usual tubing 53. At any suitable point within the path of the electric current from the protective inlet switch 54, to the electromagnetic device 21, 20 a second switch 55 is provided, operated by a gear 56 upon the upper end of its shaft 57 by means of a segment 58. The latter is mounted upon an oscillatory shaft 59 at any convenient point along the length of the 25 shaft.

We prefer to operate a separate switch by the segment, as indicated, as compared with the more simple use of the part corresponding to the segment as itself constituting the 30 movable member of the switch.

The shaft is mounted in any type of bearings 60, 61 and one of the bearings is provided with a drag or friction device to prevent the shaft from movement by jar- 35 ring and to prevent it from rebounding angularly at the ends of its stroke. The particular form of drag which we have shown uses a split in the bearing at 62 with clamps for drawing the parts together to any re- 40 quired extent about the shaft as a means of applying the friction.

The shaft 59 is of sufficient length to permit engagement by the ram or a part such as bar 63, extending therefrom, with cams 45 adjustably mounted upon the shaft as illustrated by means of clamps 64 and 65. We have preferred to form the cams themselves as fins 66 and 67, which are oppositely turned so as to be thrown in opposite angular 50 directions by the bar 63.

The adjustability of these cams offers the same flexibility of adjustment of the automatic stroke of the ram to provide for different desired heights of ram travel and different thicknesses of die, as is provided with 55 the existing mechanical form of reversal.

It is quite necessary to provide a stop for 60 limiting angular movement of the shaft 59, and also to have hand control of the current reversals to permit a short stroke ram operation, needed particularly for drawing tong holds, breaking down, cutting off stock, etc. We provide for this conveniently by a lever arm or handle 68, secured to and controlling

the throw of the shaft 59, and limited angularly in its movement by any suitable lugs or projections. Hand or treadle reversal by this lever arm leaves the cam fins 66 and 67 in the same positions for engagement by the bar 63 as would be the case with 70 full automatic operation.

In operation the main or inlet switch 54 is thrown when the hammer is to be started and, the board clamps being released by the treadle, the ram is lifted, either by 75 reason of the normal position of the switch 55, because of the position at which the ram had been left, or by movement of the handle 68.

The cams cause the switch 55 to be opened 80 at the upper end of the stroke and closed at the lower end of the stroke respectively, when they are engaged by bar 63, and the height of these cams may be varied readily to alter the point of reversal.

With the ram at the lower end of its stroke, the electromagnetic device is energized, resulting in an immediate solenoidal pull upon the armature which lifts the armature, at the same time compressing the 90 spiral spring and lifting the connections between the armature rod and the arm 29. As the armature approaches the magnet pole the latter begins to pull appreciably also. The electromagnetic pull then increases rapidly, becoming a maximum, coincidentally with contact, or the closest approach permitted, between the pole and armature faces, corresponding with complete engagement of the rolls with the board. 100

The engagement of the rolls with the board causes the ram to be lifted until the bar 63 engages the upper cam or until the shaft 59 is turned by hand to operate the switch. In either event, the current is then 105 broken and the combined expansion of the spiral spring and weight of the parts cause the front roll to be swung outwardly, releasing the board and allowing it to drop. These reversing operations will continue automatically as long as the treadle is depressed.

We have preferred to make the electromagnetic device single acting, using gravity or spring action, or both for movement in 115 the opposite direction, for the reason that operation in the reverse direction wholly or partly by solenoid or magnet, though entirely practicable, involves an unnecessary use of electric energy.

It will be evident that we can use solenoidal operation entirely, by sufficiently strengthening the solenoidal pull, or electromagnet pull alone, by shortening the stroke, and our claims are intended to cover 125 either or both of these, broadly, except where they specifically call for a different interpretation.

What we claim as new and desire to secure by Letters Patent is:—

1. A board drop hammer, comprising a frame, board-lifting mechanism, clamp mechanism and a release for the clamp in combination with an electromagnetic device and connections for drawing the lifting rolls together for engagement with the board and contact devices operated by movement of the ram for making and breaking the electric circuit.

2. In a board drop hammer having a frame, an anvil, a ram, board and elevating rolls, electromagnetic means and connections for moving one roll to bring the rolls into engagement with the board.

3. In a board drop hammer having a frame, an anvil, a ram, board and elevating rolls, electromagnetic means for moving one roll to bring the rolls into engagement with the board, and spring-operated quick release means for promptly releasing the rolls.

4. A board drop hammer having a frame, an anvil, a ram, a board and elevating rolls in combination with electromagnetic means and connections lifted thereby, with energization of the circuit to throw the rolls into gripping engagement with the board, but releasing by gravity when the circuit is interrupted.

5. A board drop hammer having a frame, an anvil, a ram, board and elevating rolls, in combination with connections for bringing the rolls into engagement with the board and a combined solenoidal and electromagnet lifting means for operating these connections.

6. A board drop hammer having a frame, an anvil, a ram, a board and elevating rolls, in combination with connections for throwing the rolls into engagement with the board, combined solenoidal and electromagnet means for lifting the connections when the current is thrown on, and connections operated by the ram for making and breaking the electric circuit.

7. A power hammer, comprising a frame, an anvil, a ram, a board and lifting rolls, with operating mechanism therefor in combination with contact making devices operated with movement of the ram, a solenoid energized when the contact is made, an armature operating in said solenoid, an arm and cam operating mechanism moving one roll toward the other with movement of the arm and connections between the arm and the armature whereby the rolls are engaged with the board when the solenoid is energized.

8. A power hammer, comprising a frame, an anvil, a ram, a board and lifting rolls, with operating mechanism therefor in combination with contact making mechanism operated with movement of the ram and a

solenoid energized when the contact is made, an armature for the solenoid, connections from the armature, moving one roll toward the other with movement of the armature into the solenoid and a magnet pole energized at the same time as energization of the solenoid and effective to draw the armature at the inner end of the latter's stroke.

9. A power hammer, comprising a frame, an anvil, a ram, a board and lifting rolls, with operating mechanism therefor, in combination with circuit closing mechanism operating with movement of the ram, a solenoid energized by the closing of the circuit, an armature movable into the solenoid and connections between the armature and one of the rolls moving the roll toward its mate with initial movement of the armature and weighted normally to withdraw the armature when the circuit is opened.

10. A power hammer, comprising a frame, an anvil, a ram, a board and lifting rolls, with operating mechanism therefor, in combination with circuit closing mechanism operating with movement of the ram, a solenoid energized by the closing of the circuit, an armature movable inwardly and outwardly with respect to the solenoid, connections between the solenoid armature and one of the rolls to move it toward the board with inward movement of the armature and normally weighted to tend to withdraw the armature from the solenoid and a spring set by inward movement of the armature and tending to assist in withdrawal thereof.

11. A power hammer, comprising a frame, an anvil, a ram, a board and lifting rolls, with operating mechanism therefor, in combination with circuit closing mechanism operating with movement of the ram, a solenoid energized by the closing of the circuit, an armature movable inwardly and outwardly with respect to the solenoid, connections between the solenoid armature and one of the rolls to move it toward the board with inward movement of the armature and normally weighted to tend to withdraw the armature from the solenoid, a spring set by inward movement of the armature and tending to assist in withdrawal therefrom, and an electromagnet pole reinforcing the pull of the solenoid upon the armature at the extreme inward position of the armature.

12. A power hammer, comprising a frame, an anvil, a ram, a board and lifting rolls, with operating mechanism therefor, in combination with circuit closing mechanism operating with movement of the ram, a solenoid energized by the closing of the circuit, an armature movable inwardly and outwardly with respect to the solenoid, connections between the solenoid armature and one of the rolls to move it toward the board with inward movement of the armature and

normally weighted to tend to withdraw the armature from the solenoid, a spring set by inward movement of the armature and tending to assist in withdrawal therefrom, and 5 an electromagnet pole energized at the same time as the energization of the solenoid and coöperating with it to retain the armature in its inward position.

13. A power hammer, comprising a frame, 10 an anvil, a ram, a board and lifting rolls, with operating mechanism therefor, in combination with a cam sleeve surrounding one of the roll shafts, a bearing for the cam sleeve, an arm connected with the cam sleeve to shift it, thereby moving the roll toward or away from the board, connections for said arm normally weighted to hold the roll away from the board and electromagnetic means energized through movement of the 15 ram near the lower extremity of its stroke to lift the connections and deenergized through the movement of the ram at the upper end of the stroke.

14. A power hammer, comprising a frame, 20 an anvil, a ram, a board and lifting rolls, having shafts with operating mechanism therefor, in combination with a cam sleeve surrounding one of the roll shafts, a bearing for the cam sleeve, an arm connected with the cam sleeve to shift it, thereby moving the roll toward the board, an armature adapted to move the connections, a solenoid connected with the armature, a spiral coil compressed by upward movement of the 25 armature, an electromagnet pole assisting the solenoid, and common means for energizing the solenoid and pole by reason of downward movement of the ram, to lift the connections and set the roll and to deenergize the solenoid and pole with upward movement of the ram to release the connections and roll.

15. A power hammer, comprising a frame, 30 an anvil, a ram, a board and lifting rolls, with operating mechanism therefor, in combination with gravity-operated means for normally releasing the rolls and electromagnetic means for lifting the gravity-released rolls, automatically energized with 35 downward movement of the ram and deenergized with upward movement of the ram.

16. A power hammer, comprising a frame, 40 an anvil, a ram, a board, and lifting rolls, with operating mechanism therefor, in combination with gravity-operated means for normally holding the rolls apart, and lifting mechanism therefor, operated by reason of downward movement of the ram and causing the rolls to engage the board.

60 17. A power hammer, comprising a frame, an anvil, a ram, a board and lifting rolls, with operating mechanism therefor, in combination with gravity-operated means for normally holding the rolls apart, lifting

mechanism therefor, operated by reason of 65 downward movement of the ram, to cause the rolls to approach each other, and a spring compressed by reason of said lifting movement and assisting in the release of the rolls when the lifting means is rendered inoperative.

18. In a board drop hammer having a frame, an anvil, a ram, a board, and lifting rolls therefor, spring-operated release mechanism for said lifting rolls, electro-magnetically operated means for setting the rolls, and circuit closing mechanism for said means, closed by reason of downward movement of the ram and opened by reason of upward movement thereof.

19. In a board drop hammer, a frame, an anvil, a ram and a board movable within the frame, operating rolls for lifting the ram, electromagnetic means for tightening the rolls against the board, an oscillatory shaft, 85 cams thereon operated by the movement of the ram, and switch mechanism opened and closed by oscillatory movement of said rod at the upper and lower limits of ram movement respectively, to open and close the circuit through the electromagnetic means.

20. In a board drop hammer, lifting rolls for the board, means for shifting one of the rolls, an armature and armature rod, connections for moving the shifting means and 95 pivotally connected with the rod, a solenoidal winding about the armature, an electromagnet energized at the same time as the solenoid, a magnet shell connected with the magnet pole and in part inclosing the solenoidal windings, and means for energizing the solenoid and magnet core with downward movement of the board and ram.

21. An electromagnetic mechanism for shifting the roll in a board drop hammer 105 comprising a solenoid and armature therefor for giving the initial movement to the roll and an electromagnet pole assisting in the final movement of the roll and holding it firmly in set position.

22. Operating mechanism for shifting the eccentric and moving the roll in a board drop hammer comprising an armature and connections adapted to release the roll by gravity movement and electromagnetic 115 means for lifting the armature and connections with energization thereof and retaining them in raised position.

23. Operating mechanism for shifting the eccentric and moving the roll in a board drop hammer comprising an armature and connections adapted to release the roll by gravity movement and electromagnetic means comprising a solenoid and magnet operating on the same armature to raise it 120 and hold it in raised position.

24. A quick-release safety operating mechanism for shifting the eccentric arm of a

board drop hammer roll which comprises a gravity-released pivoted arm connection with the eccentric arm, a spring retracted armature connected with the arm and electromagnetic means for lifting the armature to lift the arm, compress the spring and shift the roll.

25. The method of providing for quick

release of the roll in an electrically operated board drop hammer which consists in shifting the movable roll against the operation of gravity and a second resilient force and releasing the roll by the combined operation of the two resilient forces. 10
